113,013

DESIGN FOR SUNGLASSES OR SIMILAR ARTICLE

William J. Parfrey, Rutherford, N. J., assignor to Spill Manufacturing Co., Inc., East Rutherford,
N. J., a corporation of New Jersey

Application October 26, 1938, Serial No. 80,685

Term of patent 7 years

To all whom it may concern:

Be it known that I, William J. Parfrey, a citizen of the United States, residing in Rutherford, county of Bergen, State of New Jersey, have invented a new, original, and ornamental Design for Sunglasses or Similar Article, of which the following is a specification, reference being had to the accompanying drawing forming a part thereof.

Figure 1 is a perspective view of the sunglasses or similar article showing my new design; and

I claim:

The ornamental design for sunglasses or similar article, substantially as shown.

WILLIAM J. PARFREY.
